UNITED STATES PATENT OFFICE.

RONALD E. J. NORDQUIST, OF MAPLEWOOD, NEW JERSEY, ASSIGNOR TO AMERICAN CAN COMPANY, OF NEW YORK, N. Y., A CORPORATION OF NEW JERSEY.

SEMITAUTOMATIC VACUUM-CLOSING MACHINE.

Application filed March 5, 1923. Serial No. 622,744.

My present invention relates to machines for uniting can ends to filled can bodies and particularly to such machines in which the closing operation is performed in a vacuum. 5 A principal object of the invention is the provision of means for effectively closing the space about the can when the latter is in seaming position, without interfering with the rotation of the turret employed for transferring the cans, or necessitating complicated mounting thereof.

It is also an object to provide means whereby the lifting of the can to seaming position serves to automatically close the 15 bottom opening of the turret pocket in which said can is positioned and to seal the turret to the seaming head casing in such manner as to cut off communication with the outside air.

Another object is the provision of a machine of this character which is largely automatic in action and in which the rotation of the feeding turret and the closing operations are so timed, with reference to the exhaust of air, that the operations may take 25 place in rapid succession and with such cooperation as to permit a high rate of production.

Other objects and advantages of the invention will be apparent as it is better understood from the following description, which, taken in connection with the accompanying drawings, discloses a preferred embodiment thereof.

35 Referring to the drawings,

Fig. 1 is a side elevation, partially broken away, of an apparatus in which my invention is embodied;

Fig. 2 is a side elevation of the machine taken from the side opposite that shown in Fig. 1, certain parts being illustrated in section;

Fig. 3 is an end elevation, looking toward the right in Fig. 1 and with certain parts shown in section;

Fig. 4 is a top plan view, partially broken away for convenience of illustration;

Fig. 5 is an enlarged partial section through the turret and supporting frame and showing a part of the seaming head, with the can lifted to seaming position;

Fig. 6 is an enlarged sectional view of the seaming head and associated parts;

Fig. 7 is a plan view of the turret, showing in section the floating valve member for

sealing the turret pocket at the closing station;

Fig. 8 is a detail view, partially in section, showing the vacuum control valve, being taken substantially on the line 8-8 in Fig. 60 3; and

Fig. 9 is another detail showing the lateral passage from the vacuum control valve to the seaming head casing and including an elevational view of the floating valve by 65 which the turret pocket is closed.

As thus illustrated, the apparatus may be described as follows. A hollow frame part 11 is supported from the floor on a base 12 and in turn supports a relatively large casing 13 for the seaming mechanism. A turret 14 is mounted on a side extension 15, having a shelf part 16 extending laterally therefrom and forming a table across which the filled cans may be directed by hand to said 75 turret 14. Said turret is provided, in the present instance, with four pockets 17 in which the cans may be positioned and are held during rotation of the turret, suitable guides 18, 19 and 21 being provided about 80 the edge of the table part 15 whereby the cans are held in the pockets 17 as the turret revolves. A guide 20 is positioned upon a cover part 20' above the turret and extends out over the extension 16 in position to engage the upper part of the cans as they are moved to the turret. It will be understood that said turret is driven intermittently and that a can 30 is fed into a pocket 17 when the latter is at rest adjacent the table extension 16, is moved past an idle station 22, (Fig. 7) thence to a seaming station 23 and is ejected from the machine at a fourth station 24, at which there is provided a discharge chute 25. The turret stations are, 85 perhaps, best illustrated in Fig. 7.

Attention is now called to the power mechanism by which said turret 14 and the other operating parts of the machine are driven. A power shaft 26 carries a pulley 27, which 100 may be driven from any suitable source of power, said shaft being geared to a transverse shaft 28 by means of a pinion 29, a spur gear 31 and bevel gears 32 and 33 carried respectively on a short shaft, not shown, beneath the shaft 26, and upon the transverse shaft 28. Said transverse shaft carries a bevel gear 34, meshing with a bevel gear 35 on the upper end of a diagonally arranged shaft 36 extending through a sleeve 36', said 110

shaft 36 having a bevel gear 37 on the lower end thereof meshing with a bevel gear 38 upon a transverse shaft 39. Said gears 34 and 35 are contained in a casing 41 on the frame and the gears 37 and 38 are contained within a lower casing 42. Said casing also contains a Geneva wheel 43 keyed to a shaft 44 which shaft carries at its opposite end a bevel gear 45. Said gear 45 meshes with a bevel gear 46 on the lower end of a shaft 47 to the upper end of which the turret 14 is secured. The shaft 39 carries a Geneva arm 48 adapted to engage in slots 49 in the Geneva wheel 43, and it will be understood that the continuous rotation of the shaft 39 thus accomplishes an intermittent rotation of the shaft 44, since the arm 48 serves to rotate the wheel 43 merely the distance between adjacent slots 49 upon each revolution of said shaft 39. In this manner, the turret 14 is intermittently rotated for the purpose hereinbefore stated.

Means are provided to lift the cans into seaming position when they come to rest at the turret station 23 and for applying and seaming an end to hermetically close the can. In this connection, attention is called first to Figs. 1 and 3. A lift 51 is provided on the upper end of a rod 52 and disposed 25 in an opening 53 in the table 15 so that the cans are positioned upon this lift when moved to the turret station 23. Said rod 52 is secured within a sleeve 54 arranged within bearings 55 and 56 and is vertically reciprocable by means of a bifurcated arm 57 having inward projections 58 engaging in a groove 59 in a collar 61 on the lower end of said rod 52. The arm 57 is carried on a square shaft 62 at the lower end of the 30 frame, which shaft carries also an arm 63 pivotally connected at 64 with a rod 65, which latter carries at its upper end a roller 66, riding in a groove 67 of a cam 68 carried upon the transverse shaft 28. In this 35 manner, the lift 51 is periodically raised to lift a can to be seamed, to a seaming head to be now described.

Said seaming head is illustrated in detail in Fig. 6 and comprises primarily a rotatable body 69, carrying rolls 71 adapted to cooperate with a chuck 72 to unite a can end to a body by the well-known double seaming process. The body 69 is rotated about the chuck 72, by means of a sleeve 73 having screw-threaded engagement with said body at 74 and being formed with a bevel gear 75 at its upper end meshing with a bevel gear 76 carried on the power shaft 26. Suitable bearings 77 are provided to facilitate the rotation of the gear 75 and sleeve 73 about an inner sleeve 78 in which is mounted a knockout spindle 79. Said sleeve 78 has screw-threaded engagement at its upper end with a collar 81, which in turn is threaded to 40 an outer fixed sleeve 82 and an inner sleeve

83, a cap 84 being interposed between the upper end of the sleeve 82 and the inner sleeve 83.

The shaft 26 carries a second bevel gear 85, which is somewhat larger than the gear 76 and meshes with a gear 86 on the upper end of a sleeve 87 surrounding the sleeve 73. Said sleeve 87 is rotatable in bearings 88 in a bearing member 89 secured in the frame by means of a threaded collar 91 having a recess into which extends an inward projection 92 on said frame. A set-screw 93 may be employed for the adjustment of this bearing. Said sleeve 87 is formed with a gear 94 at its lower end meshing with gears 95 on the upper ends of spindles 96 upon which the rolls 71 are carried. It will be noted that said spindles are eccentrically mounted within the gears 95 and are thus moved in and out with respect to the chuck 72. It is also to be observed that, since the relative ratio between the gears 85 and 86 differs from the ratio between gears 76 and 75, there is a variance between the speed of rotation of the body 69 and of the gears 95 whereby the rolls 71 may be brought in and out in proper timed relationship during the rotation of said head 69.

A knockout disk 97 is provided on the lower end of the rod 79 and serves to remove the closed cans from the chuck 72 after the seaming operation. For this purpose, a collar 98 is provided on the upper end of said rod 79 and is connected by a pin 99 with an arm 101, which latter is secured to an upper arm 102 of a bell crank lever 103, the latter being pivoted at 104 to the frame and having a lower arm 105 carrying a roller 106 riding in a groove 107 in a cam 108 carried on the shaft 28.

The machine of my invention is provided with means for creating a vacuum in the space about the can at the seaming station, in order that a partial vacuum may exist in the closed can, this being desirable for purposes of preservation in the packing of certain products, as, for example, coffee. To this end, a valve, perhaps best illustrated in Figs. 3, 8 and 9, is employed. This valve consists of an outer fixed member 109 communicably connected with an exhaust pipe 111, and an inner movable member 112, which latter is vertically reciprocated in timed relationship to the feeding and seaming of the cans by means of a roller 113 riding in a groove 114 in the cam member 108. Said member 109 has an upper opening 115 therein which communicates with a recess 116 provided in the member 112. A second and relatively wide opening 117 is provided in the lower part of the member 109 and this opening is also communicably connected with the recess 116 when the member 112 is in the position shown in Fig. 3. In this manner, communication is established between 110 115 120 125 130

the openings 115 and 117 and it will be noted, from an inspection of Fig. 9, that the opening 117 is connected by a passageway 118 with the interior of the seaming head 111 casing 13. With the parts in the position shown in the drawings, it will be manifest that air may be withdrawn from said seaming head casing through the exhaust pipe 111. If, however, the member 112 be lifted by the cam 108 to position in which a projection 119 is in contact with the inwardly projecting part 121 on the member 109, the opening 115 will be cut off from the opening 117 and the air will enter through a passage 122 extending from the exterior of the casing. The valve part 112 is held tightly against the member 109 by means of springs 123 housed in a bracket 124 and bearing upon a friction plate 125.

By the foregoing valve construction, air is withdrawn from the seaming head casing 13 at the time the can is lifted to seaming position and the lifting of the can is also accompanied by the sealing of the opening through which said can is projected, thus making it possible to create a vacuum about the seaming area for the purpose stated. In this connection, attention is called to Figs. 1 and 5. It will be noted that a clamping ring 126 is provided in the frame surrounding the lift or plunger 51, and a disk or diaphragm 127 is secured upon the rod 52 just beneath and extending beyond said plunger 51 in position to engage the lower surface of said clamping ring 126 upon upward reciprocation of said plunger. Said diaphragm is preferably of spring material and, upon contacting with the ring 126, lifts the latter slightly from its seat, being assisted in this action by atmospheric pressure acting on the lower side of the diaphragm when the seaming chamber is vacuumized. This results in a slight lifting of the turret 14, so that the upper part thereof bears tightly against a bottom plate 128 on the seaming head casing 13. In this manner, the pocket 17 in the turret is sealed at the top and bottom, to prevent admission of outside air.

It is, however, necessary that means be provided to enclose a pocket 17 from the side when said pocket reaches the seaming station. For this purpose, I provide means, perhaps best shown in Fig. 7. A floating plate or valve 129 is provided, being feathered to the frame 11, as shown at 131, a slight space being permitted between said parts. Upon the withdrawal of air from the interior of the pocket 17, the valve 129 is drawn tightly against the turret 14 at opposite sides thereof by negative pressure within the pocket, and an effective seal is thus provided.

A finger 132 is pivoted in a recess 133 in said valve 129 and is forced inwardly by means of a spring 134 to center the can

against inward projections 135 in the pocket 17, it being understood that said can may be held loosely in said pocket until the seaming station is reached, being merely confined by the guide 18. 70

From the foregoing, it will be evident that the turret is free to rotate normally without obstruction from the valve 129, since an appreciable space is allowed between these parts, unless a vacuum be created on the interior of the casing. Furthermore, the turret may be mounted in the usual manner upon the shaft 47. The particular pocket in which the can to be closed is positioned is automatically sealed when it comes to rest beneath the seaming station, the operation of the valve 129 being so timed that the turret is again permitted to rotate freely upon the completion of the seaming action. 85

A clutch device is employed to control the operation of the machine and is best illustrated in Figs. 1 and 2. A hand lever 136 is pivoted at 137 and connected by an arm 138 and a rod 139 to an upwardly extending arm 141, which is pivoted at 143 to a bracket 143' projecting from the frame. Said arm is provided with an upper bifurcated portion 144 carrying rollers 145 disposed on opposite sides of the shaft 26 which projects from a bearing bracket 142. Said rollers 145 are adapted to engage a plate 146^a on said shaft 26, said plate being provided with laterally projecting pins 146^b which act upon a sliding member 146 feathered to said shaft 26 and forming one of the clutch members. A friction member 147 is interposed between said member 146 and the web of the pulley 27, and it will be manifest that movement of the member 146 toward the right, viewing Fig. 2, will cause the member 147 to be tightly clamped against said pulley, with consequent rotation of the member 146 and shaft 26. Said member 146 is adapted to be moved to clutching position by means of a spring 148, which is provided on the end of the shaft 26 thereby establishing connection with the continuously rotating pulley 27. When it is desired to disconnect from said pulley 27, said member 146 is moved by means of the parts heretofore described against the tension of the spring 148 to the position shown in Fig. 2. 110

The shaft 26 carries a gear 149 meshing with a gear 151 on a parallel shaft 152, which latter is provided with a hand wheel 153 for manual operation of the machine. Said shaft 152 is adapted to be moved longitudinally in bearings 154 upon manipulation of the lever 136, so that the gears 151 and 149 are thrown in mesh when the machine is not operating and are disconnected during operation. For this purpose, links 155 and 156 and an arm 157, engaging against a collar 158 on the shaft 152, are provided. 130

A graduated scale 159 is provided on the frame adjacent the floating valve member 129 to facilitate alinement for different heights of cans. A vacuum gauge 161 is 5 provided on the casing 13 and connected with the interior thereof.

It is thought that the invention and many of its attendant advantages will be understood from the foregoing description, and it 10 will be apparent that various changes may be made in the form, construction and arrangement of the parts without departing from the spirit and scope of the invention, or sacrificing all of its material advantages, the 15 form hereinbefore described being merely a preferred embodiment thereof.

The vacuum herein referred to is not to be understood as a perfect vacuum but one of practicable degree to effect or aid the 20 preservation of sealed commodities; and the closing and sealing means are similarly to be understood as being of a practicable character which may not effect the absolute exclusion of all air.

25 I claim:

1. In an apparatus for vacuumizing and sealing containers, the combination of a frame having a portion of a vacuum chamber, sealing mechanism operating in said 30 portion of a chamber, a can carrier formed with pockets each of which is adapted to be brought into position in relation with said portion of the chamber to form a complete vacuum chamber, whereupon a can which 35 has been conveyed by said pocket and placed in line with the seaming mechanism may be operated on and hermetically sealed thereby while in said vacuum chamber, and a floating element separate from said carrier and from 40 said frame and slightly movable relative thereto, and subject to atmospheric pressure and interposed between said carrier and said frame and acting to seal said vacuum chamber during the seaming operation.

45 2. In an apparatus for vacuumizing and sealing containers, the combination of a frame having a portion of a vacuum chamber, sealing mechanism operating in said portion of a chamber, a can-carrying turret 50 formed with pockets each of which is adapted to be brought into position in relation with said portion of the chamber to form a complete vacuum chamber, whereupon a can which 55 has been conveyed by said pocket and placed in line with the seaming mechanism may be operated on and hermetically sealed thereby while in said vacuum chamber, and a floating element separate from said turret and from said frame and slightly movable 60 relative thereto, and subject to atmospheric pressure and interposed between said turret and said frame and acting to seal said vacuum chamber during the seaming operation.

65 3. In an apparatus for vacuumizing and

sealing containers, the combination of a frame having a portion of a vacuum chamber, sealing mechanism operating in said portion of a chamber, a can-carrying turret formed with pockets each of which is adapted 70 to be brought into position in relation with said portion of the chamber to form a complete vacuum chamber, whereupon a can which has been conveyed by said pocket and placed in line with the seaming mechanism 75 may be operated on and hermetically sealed thereby while in said vacuum chamber, and a floating element separate from said turret and from said frame and slightly movable relative thereto, and subject to atmospheric 80 pressure and interposed between the convex face of said turret and said frame and acting to seal said vacuum chamber during the seaming operation.

4. In a machine for closing cans, the 85 combination of a casing, a can-conveying turret having pockets formed with open outer sides into which cans to be closed may be introduced, a frame carrying said turret, a movable air-excluding plate engaging said 90 frame and bearing on the side of the turret, and means for exhausting air from a pocket when the open side thereof is closed by said plate.

5. In a machine for uniting can ends to 95 filled can bodies, the combination of an intermittently rotating turret provided with vertically disposed pockets for said can bodies, mechanism for seaming an end to a body at one of the stations of said turret, means movable against the side of the turret 100 at said station for sealing the pocket against the outside air, and means for creating a vacuum in the space about the can during the seaming action.

6. In a machine for uniting can ends to filled can bodies, the combination of an intermittently rotating turret provided with vertically disposed pockets for said can bodies, mechanism for seaming an end to a body at one of the stations of said turret, means movable against the side of the turret at said station for sealing the pocket against the outside air, and means for creating a vacuum in the space about the can during 110 the seaming action, the creation of said vacuum serving to draw said movable means into sealing relationship to the turret.

7. In a machine for closing cans, the combination of a casing, a can-conveying turret 115 having pockets formed with open outer sides into which cans to be closed may be introduced, means for exhausting air from a pocket which is in closing position, and means against which the can is moved by the 120 turret for forcing the can away from the open side of the turret when the air is exhausted.

8. In a machine for closing cans, the combination of a casing, a can-conveying turret 125

having pockets formed with open outer sides into which cans to be closed may be introduced, a can-lifting plunger operating at the closing station, and a yielding disk carried 5 with the plunger and operating under atmospheric pressure to make substantially airtight the bottom end of a pocket when the latter is at the closing station and the can is lifted, and means for exhausting air from 10 such pocket.

9. In a machine for closing cans, the combination of a casing, a can-conveying turret having pockets formed with open outer sides into which cans to be closed may be introduced, air-operated means movable against 15 the turret cooperating with the turret to exclude air from a pocket which is at the closing station, and means for exhausting air from such pocket.

RONALD E. J. NORDQUIST.
